GARAGE DOOR

Anthony Basile and Victor L. Basile,
Far Rockaway, N. Y.

Application April 9, 1936, Serial No. 73,537

2 Claims. (Cl. 20—20)

This invention relates to certain new and useful improvements in garage doors.

The primary object of the invention is to provide a garage door of the sliding type wherein the door that is formed of hinged sections is adapted to be slid in an upward and rearward direction to occupy a position in proximity to the roof of the garage and interiorly thereof when in open position.

10 A further object of the invention is to provide a garage door of the foregoing character that has counter-balancing weights connected thereto by means of chains or the like to facilitate operation of the door, the latter being preferably 15 formed of two sections having a horizontal hinge connection that is tensioned to a degree to retain the door section in alignment when vertically disposed and closed, but of insufficient tension to resist a rearward swinging movement of the 20 upper section of the door after the same has started its tilting rearward movement toward open position.

A further object of the invention is to provide a garage door formed of horizontally hinged sections that are adapted to be slid upwardly and rearwardly to open position with guide tracks for the door sections for the support of the side edges of the door.

With the above and other objects in view that 30 will become apparent as the nature of the invention is better understood, the same consists in the novel form, combination and arrangement of parts hereinafter more fully described, shown in the accompanying drawings and claimed.

35 In the drawings:—

Figure 1 is a vertical cross-sectional view of a garage with the inner side of the garage door shown in elevation and further showing the counter-balancing weight for the door and the side 40 guide rails having the side edges of the door overlapping the same;

Figure 2 is a horizontal sectional view taken on line 2—2 of Figure 1 showing grooves in the outer side of the door for confining the counter-balancing weight chain;

Figure 3 is a detail sectional view taken on line 3—3 of Figure 1 showing the guard at the outer side of the garage door for the operating chain for the door latch at the inner side of the door;

Figure 4 is a detail sectional view taken on line 4—4 of Figure 1 showing an anti-friction roller carried by a side edge of the door for engagement with a guide track;

55 Figure 5 is a fragmentary vertical longitudinal

sectional view with the garage doors in closed position; and

Figure 6 is a view similar to Figure 5 with the garage doors in open position.

Referring more in detail to the accompanying drawings, there is illustrated a garage including side walls 10, a roof 11 and a front door frame 12 in which the garage door that is formed of horizontally hinged sections is mounted for sliding movement in vertical and rearward directions 10 either for closing the door opening or to occupy a position adjacent the roof 11 of the garage when in open position.

The garage door may be formed of any number of sections desired, the same being illustrated as 15 of the two-section type and formed of upper and lower sections 13 and 14 having a horizontal hinge connection 15 at their meeting edges. Coil springs 16 are associated with the hinge connection between the door sections to aid in maintaining the 20 door sections in alignment when vertically aligned in closed positions as shown in Figures 1 and 5.

Guides are associated with the vertical side edges of the door, vertical stiles 17 being secured to the door frame 12 with opposite side edges of 25 the door sections overlapping the stiles 17 as shown in Figure 2. The inner guides associated with the opposite side edges of the door sections are in the form of rails 18 slightly inclined from the vertical away from the stiles 17 as shown in 30 Figures 5 and 6, the rails 18, each having a rearwardly inclined portion 19 that continues in a rearwardly extending and slightly upwardly inclined door supporting rail section 20. A stop 21 is arranged at the rear end of each rail section 35 20.

The door sections 13 and 14 slide between the front stiles 17 and the rear guide comprising the rail sections 18, 19 and 20 and have counter-balance elements associated therewith to aid in 40 the opening and closing movement of the door. As shown more clearly in Figures 1 and 2, a chain wheel or sheave 22 is journalled in a bracket 23 depending from the garage roof 11 above the garage door opening and over which a chain 24 45 travels, a counter-balancing element being associated with each side edge of the garage door. A counter-weight 25 is attached to one end of the chain 24 and the other chain extends downwardly over the outer sides of the door sections 13 and 14 and is normally confined within longitudinally 50 extending grooves 26 in the outer faces of the door sections, the open sides of the grooves 26 being closed by the guide stiles 17 while the end 55

of the chain is anchored to the lower door section 14 adjacent the lower end thereof.

To retain the garage doors in locked condition when closed as shown in Figures 1 and 5, a latch 27 is carried by the inner face of the upper edge of the door section 13 for engagement with a keeper on a head rail of the door opening, the latch 27 carrying an operating chain 28 that passes through an opening 29 to the outer side 10 of the door as shown in Figure 3. A keeper or hood 30 overlies the free end of the operating chain 28 and access to the chain is prevented by the lock devices 31. The garage doors may be opened from the inner side of the garage as 15 the operating chain for the latch 27 is exposed, but it is necessary to release the hood 30 at the outer side of the garage doors to obtain access to the adjacent end of the operating chain 28.

When it is desired to move the garage doors 20 from the closed position shown in Figure 5 to the open position shown in Figure 6, the latch 27 is released and an upward movement imparted to the door sections. The upper edge of the upper door section 13 riding over the cam 25 face of a bar 32 with which the door section is engaged when in closed position is moved rearwardly on its hinge connection 15 with the lower door section, continued upward movement of the door sections causing the upper door section 13 30 to engage the upper guide rails 33 for further pivotal movement, the weight of the door overcoming the pressure of the springs 16 with the door section 13 moving into engagement with the guide rail sections 19. In fully opened position, the door section 13 rests upon the rail sections 20 while the lower free end of the lower door section 14 is held suspended as shown in Figure 6 by the counterbalance mechanism. Movement of the door is facilitated by anti-friction rollers 34 carried by the door sections for 35 engagement with the guide rails. To close the door, a pull is exerted on the chain 35 carried by the lower edge of the lower door section 14 and the garage door is then returned to its vertically closed position, shown in Figures 1 and 5. When so disposed, the wedge blocks 36 carried 40 by the inner sides of the lower door section 14 engage the lower guide rail sections 18 for moving the door section 14 into frictional engagement with the front guide stiles 17, while the spring connections 16 between the door sections holds the upper door section 13 similarly engaged 45 with the front guide stiles 17.

From the above detailed description of the invention, it is believed that the construction and operation thereof will at once be apparent and while there is herein shown and described the preferred embodiment of the invention, it is nevertheless to be understood that minor changes may be made therein without departing from the spirit and scope of the invention as claimed.

We claim:—

1. In a door structure of the character described, a door frame having a door opening therein, a sectional door having horizontal hinge connections and being vertically and rearwardly slidable into and out of the door frame opening, rails for guiding the door sections in their movements with the opposite edges of the doors overlapping and riding directly on a pair of the rails, counter-balancing means associated with the doors to facilitate opening and closing movements including flexible elements attached to the door and trained over sheaves and weights on the other ends of the flexible elements, the flexible elements being disposed inwardly of the edges of the door at the outer side thereof, and the door having guide grooves for the flexible elements in the outer face thereof adjacent each vertical side edge.

2. In a door structure of the character described, a door frame having a door opening 30 therein, a sectional door having horizontal hinge connections and being vertically and rearwardly slidable into and out of the door frame opening, rails for guiding the door sections in their movements with the opposite edges of the doors overlapping and riding directly on a pair of the rails, counter-balancing means associated with the doors to facilitate opening and closing movements including flexible elements attached to the door and trained over sheaves and weights on the other ends of the flexible elements, the flexible elements being disposed inwardly of the edges of the door at the outer side thereof, the door having guide grooves for the flexible elements in the outer face thereof adjacent each vertical side edge, and guide stiles for closing the open sides of the grooves and retaining the flexible elements therein when the door is in closed position.

ANTHONY BASILE,
VICTOR L. BASILE.
